UNITED STATES PATENT OFFICE.

JEAN EDOUARD TUSCHER, OF NEUCHATEL, SWITZERLAND.

CIRCUIT-BREAKING MECHANISM FOR INTERNAL-COMBUSTION ENGINES.

1,350,898.

Specification of Letters Patent. Patented Aug. 24, 1920.

Application filed May 20, 1920. Serial No. 383,010.

To all whom it may concern:

Be it known that I, JEAN EDOUARD TUSCHER, a citizen of the Swiss Republic, residing at 32 Evoie, in Neuchâtel, Switzerland, have invented new and useful Improvements in Circuit-Breaking Mechanisms for Internal-Combustion Engines, of which the following is a specification.

The present invention relates to a make and break mechanism for explosion-engines and enables the time of ignition to be varied automatically. This mechanism enables the time of ignition to be varied automatically according to the speed of the engine. It can be fitted to ignition magnetos and renders it possible to transform them immediately into magnetos giving an automatic advance of ignition without increasing the over-all dimensions of the magneto. The mechanism is based on the principle of the centrifugal governor. It comprises a device which rotates with the armature of the magneto and carries contacts inserted in the circuit to be broken, one of which is movable and is moved away from the other at desired intervals by one or more fixed abutments so as to break the circuit. This arrangement, of which the principle is known, is characterized by the fact that the rotary member can move relative to the armature which drives it through the intermediary of a governor-mass which pivots upon this member, bears against the armature and is subjected to centrifugal force. The pivotal movement of this mass under the action of centrifugal force produces the displacement desired, said displacement being variable as a function of the centrifugal force, and consequently, of the velocity of rotation, thereby causing a corresponding variation in the time or times of ignition. The present invention also relates to a particular form of the said movable contact or catch-lever, which is constituted by a curved lever pivoted near its center on the rotary member, and carrying at one extremity a contact and, at the other, a striker which comes into contact with the stationary abutment or abutments. This lever is characterized by the fact that it is brought back to circuit-closing position by a coil-spring under compression which bears against the portion carrying the contact and against the rotary member, and also by the fact that the portion which carries the striker is of greater mass than the other portion, so that

under the action of centrifugal force, the lever has a tendency to hold the contacts against each other, its action being added to that of the spring, so as to obtain a more abrupt break each time the lever is actuated by the fixed abutment or abutments. The said lever is also arranged in a special manner as regards its operation under the forces which act upon it, its insulation and the manner in which current is fed to it.

According to a modification, the spring which brings back the lever to its circuit-closing position is a leaf-spring fitted within the curve of the lever, and also serves to feed the current to the lever owing to the fact that its extremity, which bears against the movable rotary portion, is connected to the central portion, fixed to the armature but insulated therefrom, by a coiled spring which allows the current to pass. This coiled spring also serves to bring back the displaceable rotary portion to its original position relative to the said central portion and the force of this spring is calculated in accordance with the range of adjustment to be given to the apparatus.

The invention is illustrated diagrammatically, for explanatory purposes only, and in no way limitatively, in the accompanying drawings in which:

Figure 1 is a front view of the mechanism, and

Fig. 2 is a section along the broken line 2—2, Fig. 1.

Fig. 3 is a view, similar to Fig. 1, of a modification.

Fig. 4 is a section along the broken line 4—4 of Fig. 3.

The mechanism according to the invention comprises a rotary member or disk 1 which rotates with the armature of the magneto. With this end in view, it is mounted on a central portion in two pieces 2 and 3, one of which is screwed into the other and secured by a pin 4. The disk 1 can rotate on the reduced portion 5 of the part 3 between a flange 6 of the part 2 and a shoulder 7 on the part 3, but it must here be stated that this movement of rotation is limited and takes place under predetermined conditions, as will be explained below.

The part 2 has the form of a truncated cone and is keyed to the cheek of the armature, ground-connected in the usual manner to the armature which forms one of the poles of the primary circuit, and this part

2 is held in place by means of an insulated screw 8 passing through a sleeve 9 of insulating material, entrainment being insured by a key 10. The screw 8 is screwed into the insulated pole of the condenser of the magneto (not shown) which constitutes the other pole of the primary circuit of the magneto. This method of keying the part 2 is similar to the usual method of keying 10 circuit-breakers used with known magnetos.

The part 3 is cylindrical in front and is intersected by a notch, the profile 11 of which is designed according to a definite law, as will be seen below, and it acts as a 15 cam.

On a shaft 12 fixed to the rotary member or disk 1 there is pivoted a governing mass 13, which is under the influence of centrifugal force, and a prolongation, or finger, 14 20 of this mass bears against the cam 11 of the central part 3. A spring 15 mounted in a torus-shaped recess 16 in the part 3 bears, on the one hand, against this part and, on the other hand, against a face 17 perpendicular to the plane of the disk 1; in this 25 manner it tends continuously to rotate the disk 1 in the opposite direction to that indicated by the arrow 18 and thereby to bring the mass 13 back to the position shown in 30 full lines in Fig. 1.

The extent of outward movement of the mass 13 under the action of centrifugal force is limited in the following manner: The disk 1 has a central boss 19 on its front 35 face and the finger 14 of the mass 13 is recessed on its rear face so far as the line of the shoulder *a*, *b* so as to enable it to pass freely in front of the front face of the boss 19, when the centrifugal mass 13 moves outward under the action of centrifugal force. The maximum outward stroke of the mass 40 13 is limited by the fact that the shoulder *a*, *b* strikes against the central boss 19 along *a*¹, *b*¹.

45 The catch-lever of the circuit-breaker consists of a two-armed lever 20, 21; this lever can pivot about an axis 22 of the disk 1 and an insulating sleeve 23 is interposed between the lever and the axis 22. The lever is held on the axis 22 by a screw 24 and by means of an insulating washer 25, a leaf 26 which feeds current thereto from the insulated screw 8 upon which it bears, and a compressed coil spring 27 mounted 50 in a circular recess in the lever, concentric with the insulating sleeve 23. This arrangement permits of clamping the screw 24 on the axis 22 while, at the same time permitting of relative movement between the lever 55 and the leaf 26 and insuring perfect electric contact.

60 The arm 21 of the lever carries an insulated striker 28 designed to come into contact, during rotation, with the fixed abutment or abutments, (not shown) carried by

a circular casing, these abutments being arranged along a circle indicated in part in dot and dash lines in Fig. 1.

The arm 20 carries a platinum-covered contact 29 which bears against a platinum-covered contact 30 constituted by an adjustable screw which screws into a boss 31 on the disk 1 and has a lock-nut 32. The screw 30 is grounded by a carbon-contact 33 mounted in the rear face of the disk 1, behind the boss 31 and continuously pressed by a spring 34 against the cheek of the armature (not shown). 75

The lever is constantly pulled back so as to insure contact between the platinum 80 points 29 and 30 by a compressed coil-spring 35 which bears on the one hand in a recess in a boss 36 perpendicular to the front face of the disk 1 and, on the other hand, on an insulating washer 37 sunk into the corresponding face of the arm 20 of the lever. This arrangement of the returning-spring is very advantageous and forms one of the characteristics of the invention. 85

Another characteristic of the invention resides in the fact that the arm 21 of the lever is of greater mass than the arm 20, so that during rotation this arm 21, moving away under the action of centrifugal force, and aiding the action of the spring 35, tends to 90 press the two contacts 29, 30 firmly against each other, so that a better electrical engagement is had.

On the other hand, in view of the resistance of the lever to movement, which 100 resistance is due to the spring and to centrifugal force acting on the arm 21, it is advisable to make it longer than is customary, so that when the fixed abutments come in contact with the striker, the shock 105 is not too great, while being sufficient to cause breakage of the circuit. Otherwise, the shock would act in antagonism to the action of the centrifugal mass and would hinder its action. It is for these reasons 110 that the inventor has constructed the lever in the manner described, in which, in view of the length of the arm 21, the resultant of the shock and the other forces acting on the lever passes through the axis of rotation 115 of the whole mechanism.

The whole of the mechanism is balanced about the axis of rotation both from a static and from a dynamic point of view, subject to the reserves made for the movable portions subjected to centrifugal force. 120

The mechanism operates as follows:

Suppose the whole to be rotating in the direction of the arrow 18, Fig. 1, at a speed less than a given speed, the centrifugal force 125 acting on the mass 13 is not sufficient to overcome the pressure of the spring 15, and the mass 13 remains in the position shown in full lines in Fig. 1, in which moreover it is held by the fact that entrainment is effected 130

by the cam 11 of the central portion 3, 2 rotating with the armature in the direction of the arrow 18, which cam acts upon the finger 14 which it tends to push outwardly. 5 Breakage of the primary circuit (constituted by the parts 8, 26, 27, 20, 29, 30, 31, 33, between one of the poles of the condenser of the magneto and the cheek of the armature connected to ground) takes effect between the 10 contacts 29, 30, each time the circuit-breaker 20, 21 swings, that is to say, each time the striker 28 meets the fixed abutment or abutments on the casing. The point or points of ignition do not vary so long as the given 15 value of the speed is not attained.

As soon as this value is attained and in proportion as the speed increases after having exceeded it, the mass 13 moves outwardly against the action of the spring 15 and the 20 finger 14 abuts against the cam 11 and displaces the entire mechanism relative to the central portion 2, 3, in the direction of the arrow 18, that is to say, it effects an advance in the ignition. As the speed still rises this 25 displacement is accentuated and the advance in the ignition is increased. If the speed decreases the displacement takes place in the opposite direction. It can therefore be said that the variation in the point or points of 30 ignition corresponds automatically to the variation in speed.

The automatic variation in the ignition can be made proportional to the variation in speed or a function of this speed, according 35 to a law which can be chosen at will. For this purpose it is sufficient to determine the form of the finger 14 or of the cam 11, or of both of these parts by means of suitable diagrams.

40 It will be obvious that more than one governor-mass may be provided, and that the casing, not shown, which carries the fixed abutments may be displaced at will so as to vary the point of contact between these abutments and the striker; however, once the casing is brought to a certain position it can be considered as fixed, as well as the abutments which it carries, which then have no influence on the automatic variation of the 45 points of ignition.

The central portion 2, 3, instead of being connected to the cheek of the armature might be constituted by an integral part of this latter.

55 In the modification shown in Figs. 3 and 4, the spring 38 which brings back the lever 20, 21 to its circuit-closing position is a leaf-spring fitted in the curve of the lever. This spring 38 bears on the arm 21 to which it is 60 fixed by a screw 38¹ passing through a slot in the end of the spring 38. The other end of this spring bears on an insulated piece 39 fixed on the disk 1. In order to feed the current from the central screw 8 to the lever 65 20, 21 a rod 40 is screwed into the sleeve 41

insulated by a sleeve 42 from the central portion 3. This rod is also insulated from the central portion 3 and it also serves to hold the parts 3, 41 and 42 together. A helical-spring 43 is attached, on the one hand, to 70 the free end of the rod 40 and, on the other hand, to the end of the spring 38 which bears against the insulated member 39. In this way, current is fed from the central screw 8 to the lever 20, 21 by the rod 40, helical 75 spring 43, leaf spring 38 and screw 38¹.

The helical spring 43 plays, in this case, the part of the spring 15 and serves to restore the displaceable rotary member or disk 1 to its original position relative to the 80 central portion 3 and the strength of this spring is calculated according to the degree of adjustment to be given to the apparatus. Furthermore, a slight secondary adjustment can be obtained by varying the position of 85 the spring 38 relative to the arm 21 of the lever by sliding the screw 38¹ in the slot in the spring 38.

The method of operation of the apparatus according to Figs. 3 and 4 is the same as 90 that shown in Figs. 1 and 2.

I claim:

1. A circuit breaking mechanism for internal combustion engines comprising a disk, a contact carried by said disk, a two-armed 95 lever fulcrumed on said disk, a contact carried by one arm of said lever for engaging the first mentioned contact, yieldable means carried by said disk and bearing against said arm of the lever for holding the contacts normally engaged, a striker carried by the other arm of said lever adapted to move the contacts apart, a hub for said disk having a cam portion lying in the same plane with said lever, a weighted arm pivoted on 100 said disk in the same plane with said lever and having a nose adapted to coöperate with the cam portion of said hub whereby to shift the disk when the weighted arm swings outwardly under the influence of centrifugal 105 force, and means to yieldably hold the hub and disk in an initial position against the action of said nose on said cam, substantially as described.

2. A circuit breaking mechanism for internal combustion engines comprising in combination a disk rotating with the armature of the magneto but shiftable with respect thereto, a hub about which said disk is fitted to rotate having a cam portion, means 115 arranged between the hub and disk for yieldably holding the disk in an initial position with respect to the hub, a weighted arm pivoted on the disk and having a nose adapted to coöperate with the cam portion of the hub 120 for moving the disk relatively thereto when the arm swings outwardly under the influence of centrifugal force, a two-armed lever pivoted on the other side of the disk from 125 said weighted arm, a striker carried by one 130

arm of said lever for oscillating the same, contacts supported by said disk and the other arm of said lever, and means to normally hold the contacts closed, substantially 5 as described.

3. A circuit breaking mechanism for internal combustion engines comprising in combination a disk rotating with the armature of the magneto but shiftable with respect thereto, means adapted upon the rapid rotation of the disk to shift said disk with respect to the armature of the magneto, a two-armed contact lever pivoted on said disk, fixed abutments adapted to engage said 10 contact lever to break the circuit, yieldable means to hold the contact lever in the circuit closing position, and a spring biasing the disk to initial position, said spring being located in a torus-shaped recess, substantially 15 as described.

4. A circuit breaking mechanism for internal combustion engines comprising in combination a disk, a hub on which the disk is free to rotate, said hub having a torus-shaped recess therein, an arm carried by the 20 disk, a spring fitted between said arm and the torus-shaped recess for yieldably cou-

pling the disk and hub together, means on the disk acting on said hub when the mechanism exceeds a predetermined speed for 30 shifting the disk with reference to the hub, and circuit breaking mechanism carried by said disk, substantially as described.

5. A circuit-breaking mechanism for internal-combustion engines comprising in combination a disk rotating with the armature of the magneto but shiftable with respect thereto, a centrifugal governor-mass pivoted on said disk, a cam-face rotating with the armature, a finger on said governor 35 mass adapted to coöperate with said cam-face, a two armed contact lever pivoted on said disk, fixed abutments adapted to engage said contact lever to break the circuit, said finger acting through said cam-face to vary 40 the position of the disk relative to said armature a spring acting to hold the contact-lever in the circuit closing position, a spring acting against the centrifugal governor mass, said spring being located in a torus-shaped 45 recess in said disk and a leaf-spring for feeding current from the armature to said contact-lever.

JEAN EDOUARD TUSCHER.
